[57] **CLAIM**

The ornamental design for a handle fed paint roller or similar article of manufacture, substantially as shown.

DESCRIPTION

FIG. 1 is a side elevational view of a handle fed paint roller or similar article of manufacture, showing our new design;

FIG. 2 is a side elevational view thereof taken from the right hand side of FIG. 1;

FIG. 3 is a side elevational view thereof taken from the left hand side of FIG. 1;

FIG. 4 is a top plan view thereof;

FIG. 5 is a bottom plan view thereof;

FIG. 6 is a side elevational view shown with the lower portion of the handle rotated 90°.

FIG. 1

FIG. 2

FIG. 3

FIG. 4

FIG. 5

FIG. 6
